Attorney.

UNITED STATES PATENT OFFICE.

CLARENCE A. TAPLIN, OF FORESTVILLE, CONNECTICUT, ASSIGNOR TO THE TAPLIN MANUFACTURING COMPANY, OF BRISTOL, CONNECTICUT.

EGG-BEATER.

SPECIFICATION forming part of Letters Patent No. 725,507, dated April 14, 1903.

Application filed August 5, 1897. Serial No. 647,165. (No model.)

To all whom it may concern:

Be it known that I, CLARENCE A. TAPLIN, a citizen of the United States, and a resident of Forestville, in the county of Hartford and State of Connecticut, have invented certain new and useful Improvements in Egg-Beaters, of which the following is a full, clear, and exact description, whereby any one skilled in the art can make and use the same.

10 The object of my invention is to provide an egg-beater having rotary beater-arms of a well-known type and with a supporting-frame for said arms which shall have features of construction that shall provide extreme 15 strength and rigidity, and which shall avoid the defects of prior structures of this class, and which shall also contain advantages in construction which shall simplify and reduce the cost of making and add greatly to the durability of the device.

20 One form of device in the use of which these objects may be attained is illustrated in the accompanying drawings, in which—

Figure 1 is a view in side elevation of an 25 egg-beater embodying my improvement, the main gear-wheel being cut in section. Fig. 2 is a detail view, on enlarged scale, showing a portion of the frame of the egg-beater in edge view. Fig. 3 is a detail view, on enlarged scale, in section through the base of the handle at its junction with the supporting-frame.

In the accompanying drawings my improved egg-beater is shown as including a 35 handle *b*, having an offset bend *a*, a shank or stem *d*, to which the supporting-frame is rigidly secured, and a mount for the driving-wheel *c*.

The supporting-frame *f* is made, preferably, 40 of wire bent to shape, the outer end at the center being in the form of a loop *e* with parallel sides and then expanding in curved outlines and extending in two branches about parallel to each other and terminating in ends 45 *f'*, which are clamped firmly in sockets formed on opposite sides of the stem. On each branch or arm of the supporting-frame rotary pinions *g* are mounted, in mesh with each other, and the beaters *h h'* are secured to the

respective pinions by their inner ends and 50 mounted at the outer end of their rounded or center part on the arms of the loop of the supporting-frame. These beaters are of thin metal and are set in planes to revolve with reference to each other, as illustrated in Fig. 55 1 of the drawings.

A driving-wheel *c* is mounted on the frame-handle, as by means of a pivot *i*, and has on its inner face gear-teeth that mesh with the teeth on one of the pinions *g*. This wheel is 60 provided with a handle *i'*, by means of which it may be turned to drive the beaters at the required rate of speed. A bearing *k* for the wheel may be located on the frame.

An essential feature of my improvement 65 resides in the form of clamp used to secure the supporting-frame to the handle or main frame of the device. The beaters being rotatably mounted on this supporting-frame and having pinions meshing with the teeth 70 on the large gear-wheel, it is essential that the supporting-frame be rigidly secured to the handle portion of the device. In using the beater the hand of the user grasps the device and presses with considerable force on the 75 handle in order to retain the lower end of the beater in proper position in the receptacle in which it is being used. It will thus be seen that the supporting-frame must be secured to the handle in such manner as to effectually 80 resist this force and prevent the arms from being moved laterally or longitudinally, as a very slight movement in either direction would serve to destroy the operativeness of the device.

85 On the surface of the stem or base of the handle grooves *l l'* are formed, terminating in shoulders against which the inner ends of the supporting-frame rest. A crosswise groove is formed extending around the base or shank 90 of the handle, this crosswise groove being deeper than the lengthwise grooves, and a clamp *m* is wrapped about the parts and is located in this crosswise groove, compressing the members of the supporting-frame into 95 both the lengthwise and lateral grooves and firmly binding and securing the supporting-frame to the handle, so that an extremely

rigid and durable connection is formed which effectually sustains all strains put upon the supporting-arms in the use of the device.

The beater as a whole, consisting of the 5 parts combined and arranged as above described, is readily formed to shape as to the several parts and may be easily and quickly assembled to form a strong and durable beater in which many of the defects of prior 10 structures of this class are obviated.

I claim as my invention—

1. In combination with the frame of an egg-beater having a handle and a shank with lengthwise grooves formed in the surface 15 thereof and on diametrically opposite sides, a transverse groove extending around said shank and intersecting the lengthwise grooves and of a greater depth than that of the lengthwise grooves, a beater-frame having its ends 20 located in the lengthwise grooves, a band located in the transverse groove and forcing the ends of the beater-frame into the depression formed at the intersection of the transverse and lengthwise grooves, beaters rotatively

mounted on the beater-frame, and a gear- 25 wheel secured to the frame and in mesh with pinions on the beaters.

2. In combination with the frame of an egg-beater having a handle and a shank with lengthwise grooves formed in the surface 30 thereof on diametrically opposite sides of the shank, said grooves having end walls at their upper ends, a beater-frame having each end located in said grooves and against the end wall thereof, a transverse groove extending 35 around the shank and intersecting the lengthwise grooves and of a greater depth, a band located in the transverse groove and forcing the beater-frame into the depression formed by the intersection of the lengthwise and 40 transverse grooves, beaters rotatively mounted on the beater-frame, and a gear-wheel secured to the frame and in mesh with pinions on the beaters.

CLARENCE A. TAPLIN.
